ATTORNEY

UNITED STATES PATENT OFFICE.

OSCAR A. DE LONG, OF NEW YORK, N. Y.

DESIGN FOR A HOOK-AND-EYE MOUNT.

SPECIFICATION forming part of Design No. 25,992, dated September 8, 1896.

Application filed June 22, 1896. Serial No. 596,646. Term of patent 7 years.

To all whom it may concern:

Be it known that I, OSCAR A. DE LONG, a citizen of the United States, residing at New York, in the county and State of New York, 5 have invented and produced a new and original Design for Hook-and-Eye Mounts, of which the following is a specification, reference being had to the accompanying drawings, showing a part thereof.

- 10 The figure represents my new design for a hook-and-eye mount, being a plan view of the same. Said mount is substantially oblong in shape and has a border A at each of its sides. A longitudinally-dividing line B is arranged near one side edge of said mount, said line B being parallel with its contiguous side border-line A, a space being provided between said line B and its adjacent side line A. Several dividing-lines C are arranged transversely of the mount, said lines
- 15
- 20

C being parallel with and equidistant from one another and forming spaces between said dividing-lines. Subdivision-lines D are arranged parallel with and equidistant from one another longitudinally of the mount, the 25 said lines D, with the lines C, forming oblong-shaped spaces for the reception of hooks and eyes. At each of the corners of the rectangular arrangement, inclosed by the lines A and B, is a circle E.

30

What I claim is—

The design for a hook-and-eye mount, substantially as shown and described.

In testimony that I claim the foregoing I have hereunto set my hand this 13th day of 35 April, 1896.

OSCAR A. DE LONG.
